UNITED STATES PATENT OFFICE.

EDWARD MROSS AND WILLIAM ERNST, OF RACINE, WISCONSIN, ASSIGNEES TO HAMILTON BEACH MFG. CO., OF RACINE, WISCONSIN, A CORPORATION OF WISCONSIN.

MOTOR BRACKET.

Application filed April 30, 1926. Serial No. 105,767.

This invention relates to improvements in motor brackets, particularly adapted for attaching electric motors to sewing machines.

It is one of the objects of the present invention to provide a bracket attachment for sewing machines and like devices for yieldingly holding an electric motor so that the pulley or drive wheel engages the machine hand wheel.

10 A further object of the invention is to provide a motor bracket constricted so that the motor may be manually pivoted away from the hand wheel, the pivotal action being against the tension of a spring whereby 15 when the device is released it will automatically return to its wheel engaging position.

A further object of the invention is to provide a motor carrying bracket of the class described constructed so that when it 20 is pivoted to disengage the pulley wheel from the hand wheel, a pivotal dog member carried by the bracket pivoting handle will engage a portion of the bracket to lock the motor in disengaged or tilted position, which 25 position removes the pulley wheel from the hand wheel and permits the winding of bobbins.

A further object of the invention is to provide a motor bracket of the class described 30 which is easily attached to the head of a sewing machine of any type, is strong and durable, is efficient in operation, and is well adapted for the purposes described.

With the above and other objects in view 35 the invention consists of the improved motor bracket, and its parts and combinations as set forth in the claims, and all equivalents thereof.

In the accompanying drawing in which 40 the same reference characters indicate the same parts in all of the views:

Fig. 1 is an end view of a sewing machine head showing the bracket and motor in position;

45 Fig. 2 is a side view thereof; and

Fig. 3 is a sectional view taken on line 3—3 of Fig. 2.

Referring now more particularly to the drawing it will appear that the numeral 5 indicates the head portion of a sewing machine revolubly carrying a hand wheel 6. A small motor 7 is provided for electrically

propelling said hand wheel by means of the engagement between the pulley or drive wheel 8 of the motor and the hand wheel 6. 55

The invention resides particularly in a bracket employed for supporting said motor to hold it in yielding engagement with the hand wheel. Said bracket comprises a plate 9 attached to the side of the head 5 by means 60 of screws 10 and having a pair of spaced apart apertured ears 11 extending angularly outwardly therefrom. A pivot pin 12 extends through said ears and mounted thereon is a saddle shaped motor supporting 65 member 13. As clearly shown, the motor 7 is seated in the upper portion of the supporting member and is secured thereto. By this arrangement the motor and supporting member are free to pivot the rod 12 with 70 respect to the head but any pivotal action away from the head is against the tension exerted by a curved flat plate spring member 14. Said spring plate is bent so as to engage the pivot rod 12 and its inner end is 75 angular to fixedly engage under the plate 9, as at 16.

The pivot rod 12 is extended laterally and carries a sleeve 17. Clamped to said end portion of the rod, against the sleeve, by 80 means of a threaded cap 18, is a lever arm 19, shaped as shown in Figs. 1 and 2. Said lever arm has an upper horizontal off-set portion 20, positioned between the head 5 and the inner side of the motor to engage 85 the motor. The free end of the lever arm is off-set horizontally in the opposite direction, as at 21, to normally ride on the surface of the operating handle 22 pivoted to the machine head by means of a screw 23. 90

The operation of the bracket is such that when the handle 22 is manually lifted, the lever arm 19 will be pivoted thereby to move the saddle and motor, as shown in dotted lines, against the tension of the spring member, and wherein the pulley wheel disengages the hand wheel. In this position the motor may be locked by means of a pivotal dog 24 secured to the operating handle, as at 24', engaging a notch or shoulder 25 enlarged portion of the pivot screw 23. When the motor is thus disengaged, bobbins may be readily wound and when it is desired to return the motor to normal engaging posi-

tion, it is merely necessary to pivot the dog to disengage the notch and the spring will return the parts to normal position.

From the foregoing description it will be seen that the improved motor bracket is of very simple and novel construction, and is well adapted for the purposes set forth.

What I claim as my invention is:

1. The combination with a sewing machine head having a hand wheel, of a motor bracket, comprising a bearing member secured to the side of the head, a saddle member pivotally carried by said bearing member, spring means engaging the saddle member for yieldingly holding it in a normal position, a handle member connected with said saddle member for pivoting it away from said head, and means for releasably locking the saddle member in pivoted position.
2. The combination with a sewing machine head having a hand wheel, of a motor bracket, comprising a bearing member secured to the side of the head, a saddle member pivotally carried by the bearing member, spring means engaging the saddle member for yieldingly holding it in a normal position, a lever member associated with said saddle member for pivoting it, and a handle pivoted to the head and engaging the lever member to move it.
3. The combination with a sewing machine head having a hand wheel, of a motor bracket, comprising a bearing member secured to the side of the head, a saddle member pivotally carried by the bearing member,

spring means engaging the saddle member for yieldingly holding it in a normal position, a lever member associated with said saddle member for pivoting it, a handle, a pin pivotally connecting the handle to the head, said handle engaging the lever member to move it, a portion of said pivot pin being provided with a notch, and a dog member pivoted to the handle and engageable with said notch upon movement of the handle to releasably lock the device in pivoted position.

4. In combination, a sewing machine head having a hand wheel, a plate member secured to the side of the head and having a pair of projecting ears, a pivot rod extending through said ears, a saddle member mounted on said pivot rod, a motor carried by said saddle member, the pulley wheel of said motor normally being in engagement with said hand wheel, a plate spring member supported by said rod and engaging the plate member at one end and the saddle member at the other end portion, a lever member engaging the motor and secured to the pivot rod, a handle, a pin pivotally connecting the handle to the head, said handle engaging the lever member to move it, a portion of said pivot pin being provided with a notch, and a dog pivotally carried by the handle, said dog being engageable with said notch.

In testimony whereof, we affix our signatures.

EDWARD MROSS.
WILLIAM ERNST.
